UNITED STATES PATENT OFFICE.

WILLIAM J. CHELEY, OF CASPER, WYOMING, AND WARREN F. BLEECKER, OF BOULDER, COLORADO, ASSIGNORS TO ZERO HOUR TORPEDO COMPANY, OF CASPER, WYOMING.

WELL-EXPLODING DEVICE.

Application filed September 11, 1924. Serial No. 737,178.

To all whom it may concern:

Be it known that we, WILLIAM J. CHELEY and WARREN F. BLEECKER, citizens of the United States, residing at Casper and Boulder, in the counties of Natrona and Boulder and States of Wyoming and Colorado, have invented certain new and useful Improvements in Well-Exploding Devices, of which the following is a specification.

10. The present invention relates to a well shooting appliance, and has for its object to provide a device of this character which embodies novel features of construction, whereby a charge of high explosives such as dynamite, glycerin or the like can be safely and effectively exploded in a well.

In connection with oil, gas and water wells the expedient is sometimes resorted to of exploding a charge of high explosives 20 in the well in an effort to revive or increase the flow thereof. The setting and firing of a charge of high explosive in a deep well is ordinarily accompanied with a certain amount of danger and there have been serious 25 accidents occasioned by the premature or untimely explosion of the charge.

Among the objects of the present invention is to provide a well shooting device which is a self-contained unit, so that it 30 can be readily lowered into the well, and which provides for the proper timing and firing of the explosive charge with as little danger as possible.

The timing element is designed as a separate unit which can be properly tested out and adjusted before it is placed in position, and where a clock or watch is used means may be provided for preventing magnetic forces in the earth from interfering with 40 the proper action of the watch.

While one particular embodiment of the invention will be shown and described for illustrative purposes, it will be understood that it is possible to make many modifications and changes in the details of construction without departing from the scope of the invention.

For a full understanding of the invention reference is to be had to the following description and accompanying drawings in which,

Figure 1 is a vertical sectional view through a well shooting device which is constructed in accordance with the invention,

showing the same as completely assembled 55 and ready to be lowered into the well.

Figure 2 is a view showing the device as packed in sand within the container which is utilized for lowering the device into the well.

Figure 3 is a detail view of the battery, watch and caps.

Figure 4 is a detail view of the timer containing shell, parts being broken away.

Figure 5 is a detail view of the battery 65 and timer.

Figure 6 is a plan view of the inner face of the watch crystal showing the manner of applying the contact thereto.

Figure 7 is an enlarged sectional view 70 through a portion of the watch crystal and adjacent parts of the watch, showing the contact element which is carried by the crystal.

Figure 8 is a transverse sectional view 75 on the line 8-8 of Figure 1, looking in the direction of the arrows.

Corresponding and like parts are referred to in the following description and indicated on all of the views of the drawings 80 by like reference characters.

Referring to Figure 1 of the drawings, the numeral 1 designates an outer metallic shell which has an elongated tubular formation and is adapted to be closed at its upper end by means of a cap 2. A gasket 3, which may be of any suitable material such as lead, is interposed between the cap and the top of the outer shell 1, so as to form a tight joint when the cap is placed in position. This outer shell 1 is preferably formed of some material, such as iron, which is a ready conductor of magnetic lines of force, so that there will be no possibility of the metal parts of the watch or the timing mechanism which is used within the shell 1 being acted upon by any magnetic force in such a way as to prevent the timing mechanism from operating in the desired manner. Cast iron will constitute a 100 very satisfactory metal from which the outer iron shell 1 may be constructed, for the reason that it is very frangible and will not interfere with the proper explosion of the dynamite or other explosive, and will at the same time provide a path for the lines of force of any magnetic field which might be encountered, so that the lines of

force will not go through the interior of the shell.

Fitting closely within the outer shell 1 is the explosive and timer containing shell 4, which may be formed of any suitable material, such as card-board, which is suitably treated to render it water-proof. The shell 4 is of a proper size and shape as to completely fill the outer metallic shell 1 and, if desired, the shell 4 may be provided with a cap 5.

Fitting within the upper end of the inner shell 4 is a timer containing casing 6, the latter having a cross section corresponding to the interior of the shell 4, so that it will have a snug fit therein. The casing 6 is subdivided by a transverse partition 7 into an upper compartment 8 in which the timing mechanism proper is located, and a lower compartment 9 which receives the caps 10. The lower compartment is open at the bottom thereof, so that the lower ends of the caps project beyond the casing.

A battery 11 fits within the upper compartment 8. This battery may be of the usual dry cell type, and an L-shaped bracket 12 has one end thereof soldered or otherwise secured to the upper terminal of the battery. The other end of the bracket 12 is soldered or otherwise suitably secured to a suitable timing mechanism, such as the watch 13, said watch being provided with a glass crystal 14 and an hour hand 15. The minute hand of the watch will be broken off or removed. The watch or chronometer is thus rigidly connected to the battery so that it is held in a fixed relation thereto and the metallic parts of the watch are in electrical connection with the upper terminal of the battery.

The hour hand of the chronometer forms one of the contacts of the time controlled electric switch, while the other contact is formed by a piece of spring wire 16, which projects through an opening in the corresponding crystal 14 into the path of the hour hand. The inner end of the spring wire 16 is inclined in the direction of movement of the hour hand 15, so that the hour hand can pass under the contact wire after it has made proper contact therewith. The face of the watch may be insulated, as indicated at 16^a, opposite the spring contact wire 16, to avoid possibility of a short circuit through the watch. The outer end of the contact wire 16 is soldered, or otherwise secured to the end of an insulated lead wire 17, said wire being securely fastened to the front of the watch crystal 14 by means of non-conducting material such as linen threads 18 which are inserted through openings in the watch crystal and wrapped around the wire. A lashing is thus provided for holding the lead wire in proper position on the face of the watch, so that

there will be no danger of the wire becoming accidentally displaced and permitting the circuit to be prematurely closed. The lead wire 17 extends downwardly on one side of the battery, and a groove 19 is provided on the interior of the casing 6 at one side of the battery receiving seat for the reception of the wire. A second wire 20 is soldered or otherwise properly secured to the bottom of the battery 11, and these two wires 17 and 20 extend through suitable openings in the transverse partition 7 into the lower compartment 9 of the casing 6. The lower ends of these two wires 17 and 20 are connected in parallel to the two caps 10. The two caps are thus connected in such a manner that if either one of the caps should fail the other cap will explode and the use of the two caps practically eliminates the possibility of a failure of the device to operate properly due to a failure of the caps.

The watch or chronometer 13 can be properly tested out before the caps are applied, and the proper operation of the contacts of the time controlled switch can also be tested out by substituting a small electric light for the caps. After the chronometer and switch have been tested out and found to be operating properly, the hour hand of the chronometer can be set so that the switch will be closed within a predetermined time, said time ordinarily to be not less than one hour or more than eleven hours. When the caps are then connected the timing and exploding device will be ready as a unit for use. After the device has been properly set the cover 21 should be applied to the top of the casing, and this cover should never be removed after it has once been put in place. The chronometer and wires are all effectively sealed within the casing, so that the device can be handled as a unit without any danger of the wires being pulled out of position in such a way as to destroy the adjustment or possibly close the circuit prematurely with disastrous results.

The charge of high explosives 22 is placed in the bottom of the inner shell 4, after which the timing and exploding unit, which has been set as previously described, is inserted in position in the top of the inner shell 4. The caps 10 project beyond the end of the casing 6, so that they will be brought into effective contact with the high explosive 22. The inner shell 2 is then placed in position in the outer shell 1, the inner shell being first closed by the cap 5 and the outer shell being closed by the cap 2. The device must now be lowered into the well, and for this purpose a container 23, such as that shown in Figure 2, may be used. This container has an elongated formation so that it will pass through

the bore of the well and the upper end of the container is provided with a suitable bail 24. The container may be partially filled with sand 25 and the well exploding device packed in the sand. After the device has been lowered into position all persons are kept at a safe distance from the well until after the explosion, which should take place at the predetermined time. It will be understood that the hour hand 15 of the chronometer may be set so that it will be brought into engagement with the resilient contact wire 16 within a certain predetermined number of hours from the time of setting, and the charge will be exploded at that time. The contact of the hour hand 15 with the contact wire 16 will close the battery circuit through the caps 10. This will explode the caps in the usual manner and the explosion of the caps acts to explode the dynamite 22. One cap is sufficient to explode the dynamite, although two caps are used to guard against a possibility of failure on the part of one of the caps.

The timer is firmly anchored to the battery and the entire electrical device is completely housed within and protected by a casing so that it is impossible to obtain access thereto after it has been set. In handling the timing device after it has been set there is no possibility of destroying the wires or breaking the connections and the electrical device is not placed in operative position within the inner casing until after it has been set and sealed so that there is no danger of moving the wires to prematurely close the circuit. The construction of the device is such that the charge of high explosive can be handled and discharged at the bottom of the well with a minimum amount of danger and if ordinary care is used there will be no possibility of a premature or untimely explosion.

The timer containing shell 4 may be formed of some suitable material such as cardboard, and this tubular cardboard shell can be used as a mailing tube for the casing 6 and timer elements mounted therein. The pasteboard tube 4 thus serves as a shell for holding the parts when they are assembled for use and also as a tube for carrying the timing parts if they are sent through the mails. The timing parts can be mailed from the manufacturer to the user in the tube 4, and in the event any defect should be discovered in the timing mechanism the latter can be remailed to the manufacturer in the said tube. There is thus no extra expense involved in providing a mailing receptacle for use in sending the timing device from the manufacturer to the consumer or from the consumer to the manufacturer.

Having thus described our invention what

we claim as new and desire to secure by Letters Patent is,

1. A well shooting device including an iron shell, a removable cap forming a water tight closure for the iron shell, an explosive receiving shell fitted within the iron shell, and time controlled means for firing the explosive at a predetermined time arranged within the explosive receiving shell, the iron shell providing a water tight housing for the explosive and timing means and also protecting the timing means from the action of a magnetic field.

2. A well shooting device comprising an explosive receiving shell, an electrical timer unit including a time controlled electric switch, and a cap mounted upon and carried by the timer unit whereby the timer and cap are handled and applied as a unit to the explosive receiving shell after the explosive has been placed in the shell.

3. A well shooting device comprising an explosive receiving shell, a timer casing fitting within the shell, an electric battery arranged within the timer casing, a time controlled switch mounted upon and carried by the battery, and a cap mounted upon and carried by the timer casing, said cap being operatively connected with the battery and the time switch and the battery, time switch and cap being adapted to be handled as a unit.

4. A well shooting device comprising an explosive receiving shell, a timer casing applied thereto and formed with two compartments, an electrical timer unit fitted in one of the compartments, a closure for the said compartment, and a cap fitted in the other compartment and controlled by the timer unit, the cap and timer unit being adapted to be handled as a unit.

5. A well shooting device comprising a tubular shell adapted to be used as a mailing tube, and a timer casing fitted within the shell so that it can either be mailed within the shell or supported in operative position thereby.

6. A well shooting device comprising an explosive receiving shell, a timer casing applied thereto and formed with a compartment, a battery removably fitted in the compartment, a chronometer connected to and carried by the battery, a time controlled switch actuated by the chronometer, and an initial exploder in the circuit with the battery and time controlled switch.

7. A well shooting device comprising an explosive receiving shell, a timer casing applied thereto, a battery within the timer casing, a chronometer carried by one terminal of the battery and including a movable hand and crystal, a contact wire projecting through the crystal into the path of the movable hand, and an initial exploder arranged in the battery circuit with the contact member.

8. A well shooting device including an explosive receiving shell, a timer casing, a battery within the timer casing, a chronometer carried by one terminal of the battery and having a crystal and a movable hand, a contact wire projecting through the crystal into the path of the movable hand, a lead wire connected to the contact wire and fastened to the crystal, and an initial exploder arranged in the battery circuit with the lead wire and contact wire. 50
9. A well shooting device including an electrical timer unit comprising a battery, a chronometer carried by one terminal of the battery and having a movable hand and a crystal, a contact wire projecting through the crystal into the path of the movable hand, circuit wires connecting the said contact wire to the other terminal of the battery, and an initial exploder interposed in the said circuit wires. 60
10. A well shooting device including an electrical timer unit which comprises a battery, a chronometer carried by one terminal of the battery and having a movable hand and a perforated crystal, a contact wire projecting through the crystal into the path of the hand, a lead wire connected to the contact wire, fastening means engaging the perforations of the crystal for securing the lead wire thereto, and an initial exploder interposed in the battery circuit with the lead wire. 70
11. A well shooting device including an electrical timer unit comprising a casing formed with two compartments, a battery fitted removably within one compartment, a chronometer mounted upon and carried by one terminal of the battery, and having a crystal and a movable hand, a contact wire projecting through the crystal into the path of the movable hand, lead wires extending from the other battery terminal and the contact wire to the other compartment of the casing, and an initial exploder arranged within the said other compartment and connected to the lead wires. 80
12. A well shooting device of the character described, including an explosive receiving shell, a self-contained electric timer unit mounted upon the shell for firing the explosive charge at a predetermined time, and means enclosing the electric timer unit for protecting the same from the action of a magnetic field. 85
13. A well shooting device of the character described, comprising an explosive carrying means, a self-contained electric timer unit mounted upon the explosive carrying means, and an iron shell providing a water-tight housing for the explosive and timer unit and also protecting the electric timer unit from the action of a magnetic field. 90
14. A well shooting device comprising an explosive receiving shell, a timer unit, and a cap mounted upon and carried by the timer unit, whereby the timer and cap are handled and applied as a unit to the explosive receiving shell after the explosive has been placed in the shell. 95
15. A well shooting device comprising an explosive receiving shell, an electric timer unit, a cap mounted upon and carried by the timer unit whereby the timer and cap are handled and applied as a unit to the explosive receiving shell after the explosive has been placed in the shell, and an iron shell providing a water-tight housing for the explosive receiving shell and also protecting the electrical timer unit from the action of a magnetic field. 100
16. A well shooting device of the character described including a mechanical timer unit of a kind influenced by a magnetic field and adapted to fire an explosive charge at a predetermined time, means for protecting the timer unit from the action of a magnetic field, and an explosive charge adapted to be fired by the timer unit. 105

In testimony whereof we affix our signatures.
